Primary Examiner — Omeed Agilee
Assistant Examiner — David Truong

(57) **CLAIM**

The ornamental design for a nail polish bottle, as shown and described.

DESCRIPTION

FIG. 1 is a perspective view of a nail polish bottle showing my new design.

FIG. 2 is a front view of a nail polish bottle.

FIG. 3 is a rear view of a nail polish bottle.

FIG. 4 is a left side view of a nail polish bottle.

FIG. 5 is a right side view of a nail polish bottle.

FIG. 6 is a top view of a nail polish bottle; and,

FIG. 7 is a bottom view of a nail polish bottle.

The dash-dash lines in the drawings depict portions of the nail polish bottle that form no part of the claimed design. The dash-dot lines in the drawings depict boundaries of the claimed design that form no part thereof.

1 Claim, 7 Drawing Sheets
